UNITED STATES PATENT OFFICE.

GAVIN RAINNIE AND GEORGE J. A. ROBINSON, OF ST. JOHN, NEW BRUNSWICK, CANADA.

IRON FENCE-POST.

SPECIFICATION forming part of Letters Patent No. 233,018, dated October 5, 1880.

Application filed March 29, 1880. (No model.)

To all whom it may concern:

Be it known that we, GAVIN RAINNIE and GEORGE J. A. ROBINSON, of St. John, Province of New Brunswick, Dominion of Canada, 5 have invented a new and useful Improvement in Iron Fence-Posts, of which the following is a specification.

Figure 1 is a perspective view of a corner-post. Fig. 2 is a rear view of a line-post. Fig. 10 3 is a sectional elevation taken through the line *x x*, Fig. 4. Fig. 4 is a cross-section taken through the line *y y*, Fig. 3.

Similar letters of reference indicate corresponding parts.

15 The object of this invention is to furnish iron fence-posts so constructed as to be light, strong, and durable, which cannot be thrown out by the frost, and will not be liable to sway.

The invention consists in constructing an 20 iron fence-post of a body made U-shaped in its cross-section, and having hooked lugs to receive the fence-wires, the base cast hollow and solid with the body, and having holes in its top and bottom and ribs upon its inner 25 surface to receive and bind the ground-rods, as will be hereinafter fully described.

A represents the body of the post, and B the base. The body A of the post is made U-shaped in its cross-section, as shown in Fig. 4, 30 and tapers gradually from its base to its top. Upon the lower end of the body A is cast the base B, which is made in the shape of an inverted circular or flattened cone with a concaved top. The base B is cast hollow and may 35 have openings in its sides to make it lighter. In the top of the base B are formed two or more holes, C, to receive the rods D, which pass down through the cavity of the said base and out through an aperture, E, in its bottom,

where they cross each other, as shown in the 40 drawings. Upon the inner surface of the sides of the base B are formed projections or ribs F, to rest against the rods D and bind them in place.

Two rods, D, will generally be sufficient to 45 hold the posts firmly in place, but at the corners of the fence a third rod may be added. The rods D are driven through the base B into the ground, and by their position hold the posts firmly in place.

Upon the body A are cast hook-lugs G, to receive the wires H, and which are so arranged that the wires H will be slightly bent at the edges or corners of the posts, so as to be held firmly in place.

Having thus described our invention, we claim as new and desire to secure by Letters Patent—

1. An iron fence-post constructed, substantially as herein shown and described, of the 60 body A, made U-shaped in its cross-section, and having hook-lugs G, the base B, cast hollow and solid with the body A, and having holes C E in its top and bottom and ribs F upon its inner surface, and two or more rods, 65 D, substantially as herein shown and described.

2. In an iron fence-post, the base B, cast hollow, and having holes C E and ribs F, substantially as herein shown and described, to 70 receive the rods D and bind them in place, as set forth.

GAVIN RAINNIE.

GEORGE JOSEPH APPLETON ROBINSON.
